PROCESS FOR UNIFORMLY WAVING
DAMAGED HAIR

Robert Allen Wall, Darien, and Percy Fainer, Ridgefield, Conn., assignors to Clairol Incorporated, New York, N.Y., a corporation of Delaware
No Drawing. Filed Nov. 9, 1964, Ser. No. 410,000
6 Claims. (Cl. 424—72)

ABSTRACT OF THE DISCLOSURE

A process for uniformly waving previously damaged hair resulting in non-uniformly porous hair which involves pre-treating the hair with an aqueous acidic oxidizing agent capable of arresting the waving action of a waving composition, e.g., aqueous alkaline thioglycollic acid, and thereafter subjecting said hair to the action of said thioglycollic acid composition, whereby the hair is given a uniform wave.

This invention relates to a process for safely imparting a uniform permanent wave to unduly porous hair, and particularly to non-uniformly porous hair. This porosity and non-uniformity of porosity may result from earlier bleaching treatments or tinting with oxidation dye compositions or other hair treatments or conditions which tend to damage hair.

Living hair which has been bleached requires periodic treatment to take care of the new hair growth that occurs at the root section of the hair, i.e., the section of the hair strand closest to the scalp. This treatment, known as the retouch process, involves the application of bleach near said root section for the purpose of giving the new growth the same color as the previously bleached portions of the hair, so as to give the whole head a uniform color. Although this treatment is designed to bleach only the new hair growth, it invariably also results in subjecting already bleached hair to an additional bleaching action. As the process is repeated, portions of the hair receive a different number of multiple bleaching treatments.

In the treatment of hair known in this art as "tinting with oxidation dyes" a dye is applied to the hair whose color development requires the action of an oxidizing agent which is generally kept separate from the dye until the dye is applied to the head. Although the function of the oxidizing agent in this instance is not primarily to bleach hair, its presence on the hair serves to effect the hair in substantially the similar manner as it was added simply for the purpose of bleaching the hair. Thus, repeated tinting of hair with oxidation dye compositions is substantially equivalent in effect to multiple bleaching treatments insofar as this invention is concerned.

One effect of multiple bleaching treatments of hair is to increase the porosity and damage of the hair, the degree of porosity and damage being a function of the number of bleaching treatments that the particular hair section has been subjected to. By continual retouching the porosity of the hair changes and is made non-uniform so that it may be progressively more porous from the root section to the end section of the hair. A similar condition results from multiple tintings with oxidation dye composition. This phenomenon complicates the cold waving process of bleached hair.

Cold waving of hair is generally effected by winding hair on a curler and then applying a waving lotion which employs a reducing agent as the principal active ingredient (e.g., dilute alkaline thioglycollic acid solution). After a suitable period of time (usually 10 minutes), the hair, while still on the roller, is rinsed with water, towel blotted and treated with an oxidative neutralizing agent which

2

stops the action of the waving lotion (and, according to generally accepted theory, restores the disulfide bonds ruptured by the waving lotion). After about 5 minutes, the hair is rinsed, the curlers removed and the hair set. The degree to which a section of a hair strand will be waved is dependent on the amount of waving lotion that gets into it which in turn is a function of the porosity of the particular hair section. Thus, for any given concentration of wave lotion, all other things being equal, the more porous hair is given a greater wave and the less porous hair is given a lesser wave.

Moreover, non-uniformly porous hair, as for example, hair that has been bleached and subjected to one or more retouching treatments or subjected to multiple tintings with oxidation dye compositions, cannot be uniformly waved using the prior art techniques. Thus, for instance, if a waving lotion designed for use on bleached hair, i.e., hair having a greater porosity than unbleached hair, is employed, it is found that the end sections of the hair are well-waved, whereas the root sections of the hair are only weakly waved. If waving solutions are utilized which are strong enough to wave the root sections of the bleached hair, i.e., the new hair growth, there results an over-processing and severe hair damage and breakage at the end section or more porous sections of the hair.

It has now been found, in accordance with the present invention, that the above difficulties can be avoided by pretreating the non-uniformly porous hair, produced by prior bleaching treatments, prior tinting with oxidation dye compositions or otherwise, with a pre-neutralizing agent for a hair waving composition and then applying said hair waving composition in ordinary strength to obtain the desired uniform wave.

As used herein, the term "pre-neutralizing agent" describes a neutralizing agent that is applied to the hair prior to the application of the hair waving composition and is to be distinguished from the final neutralizers applied after the application of the hair waving composition.

It is accordingly an object of the present invention to provide a process for safely imparting a uniform wave to non-uniformly porous hair, such as hair subjected to previous bleaching treatment or treatments or tintings with oxidation dye compositions.

It is also an object of the present invention to provide a process for safely imparting a uniform wave to non-uniformly porous hair, e.g., previously bleached hair or hair tinted with oxidation dye compositions, which can be effected through the use of a single waving solution regardless of the degree of porosity or non-uniformity of porosity of the hair.

It is a further object of the present invention to provide a process for safely imparting a uniform wave to non-uniformly porous hair resulting from previous bleaching and retouching treatments or oxidation dye composition treatments which involves pretreating the hair with a pre-neutralizing agent for a cold hair waving solution prior to the application of the cold hair waving solution.

Other and more detailed objects of this invention will become apparent from the following description and claims.

As mentioned above, the process of the present invention is of particular use in the connection with hair damaged by previous bleaching treatments or tinting treatments employing oxidation dye compositions. Any of the known hair bleaching compositions and oxidation dye hair-tinting compositions will produce the undue porosity of hair mentioned supra. Typical hair bleaches which will bring this condition about are shown in "Cosmetics, Science and Technology" by Edward Sagarin (1957), pages 480 through 484. Similarly, typical oxidation dye compositions which will bring about said hair

damage is also shown in Sagarin's book on pages 503 through 512.

To illustrate the comparative merits of the present process as compared with prior art processes, the experimental development of porous hair through the use of a hair bleach or a tinting oxidation dye composition is desirable. For this purpose two compositions identified below as (A) Hair Bleach Composition or (B) Tinting Oxidation Dye Composition were prepared. Hair which is referred to herein as bleached hair is hair which has been treated with composition (A). Hair referred to as tinted hair is hair which has been treated with composition (B).

(A) Hair bleach composition

Component (a):	Percent
Oleic acid	24
Triton X-15 (glycol ether of p-ter. acetylphenol)	13
Igepal C.A. 630 (octylphenoxy polyethoxyethanol average M.W. 646)	25
NH ₃ (as 28% NH ₃ in H ₂ O)	2
Isopropanol	15
Propylene glycol	15
H ₂ O	6

Component (b):	Percent
Aqueous H ₂ O ₂	6

Component (c) (accelerator):	Percent
Ammonium persulfate	17
Potassium persulfate	67
Sodium silicate	11
Sodium carbonate	5

In use 2 ounces of component (a), 4 ounces of component (b) and about 21 grams of component (c) are mixed together and applied to the hair for 1-2 hours, unless otherwise specified.

(B) Tinting oxidation dye composition

Component (a).—Same as component (a) in composition (A) above, except that it contains 3.75% p-phenylenediamine, .06% 1,5-dihydroxynaphthalene, .05% p-aminodiphenylamine. In place of the 6% water, 2.14% water is used.

Component (b).—6% aqueous H₂O₂. In use 2 ounces of component (a) and 2 ounces of component (b) are mixed together and applied to the hair and left in contact therewith for 30-60 minutes.

It is current practice with commercial permanent wave preparation to recommend alkaline thioglycollate permanent waving lotions of various strengths depending on the degree of damage of the hair to be waved; lower strength solutions being recommended for hair having the greater degree of damage. In general, decreasing strength of the waving lotions is accomplished by lowering the thioglycollic acid concentration along with the alkalinity.

Examples of three typical commercial waving lotions are given in Table I:

TABLE I

Waving Lotion	Percent NH ₃	Percent Thioglycolic Acid
"N" for Normal Hair	2.0	7.6
"T" for Oxidation Dye Tinted Hair	1.0	3.8
"B" for Bleached Hair	0.5	1.9

The following experiment was carried out to illustrate the effect of waving bleached hair with Lotions "T" and "B" described above: Hair subjected to different degrees of damage were waved out with Waving Lotions "T" and "B" for 10 minutes and neutralized with 12% aqueous sodium bromate. The different degrees of damage were produced experimentally by subjecting hair samples to a different number of the same bleaching treatments. The least damaged hair is designated as "Root" hair, while intermediately damaged hair and heavily damaged hair

are referred to as "Shaft" and "Ends" respectively. The hair sample employed was normal brown hair and the number of bleaches that each type of hair were subjected to is as follows:

- 5 Root—1 two-hour bleach.
Shaft—2 two-hour bleaches.
Ends—3 two-hour bleaches.

10 The wet waving efficiency (see Proc. Sci. Sec. TGA, Dec. 1956, p. 12) and the strength of the hair was determined. The latter is expressed in arbitrary strength units related to the tensile modulus—the higher the number, the greater the hair strength. The results obtained are shown in Table II:

TABLE II

Hair Used	Percent Wet Waving Efficiency		Strength	
	Lotion "T"	Lotion "B"	Lotion "T"	Lotion "B"
Root	50	40	40	44
Shaft	70	55	20	25
Ends	65	70	9	13

These results show the non-uniformity in waving efficiency obtained with both the lotion for bleached and for tinted hair. In addition, the higher degree of damage imparted to the ends by the lotion for tinted hair is shown.

25 In contrast to the current commercial practice which requires a waving lotion of different strength for hair of different degrees of damage, the present invention makes it possible to use a single waving lotion or other waving composition to wave any hair regardless of its degree of damage and the non-uniformity of its porosity. As mentioned above, this is accomplished by pretreating the hair to be waved with a pre-neutralizing agent for the cold waving composition to be employed. This pretreatment may then be followed by the application of the cold waving composition and technique.

30 The term pre-neutralizing agent as employed herein is not used in its limited sense to only designate an agent whose function is merely to change the pH of waving compositions. It is used rather in its broad sense to designate any material which has a tendency to arrest the hair waving action of the waving composition that is to be subsequently applied. The mechanism of this arrest may involve: (a) a change in pH to the acid side, (b) oxidation of the active component of the waving composition, (c) a combination of (a) and (b), (d) dilution of the waving lotion, etc.

35 The particular pre-neutralizing agent or agents that are employed in accordance with the present invention need not be of any special type. Their selection will of course depend on the nature of the hair waving composition which is to be subsequently used. In general, however, the pre-neutralizing agent will be of the oxidizing type and will function by the oxidation of the active components of the waving composition to an inactive form. A variety of neutralizing agents of the oxidizing type which may serve as pre-neutralizing agents are known in the prior art and may be used in this invention. Typical among 40 these are those shown in "Cosmetics, Science and Technology," by Edward Sagarin, Interscience Publishers, Inc., New York, 1957, pages 617 through 620. These include hydrogen peroxide, alkali-metal bromates, alkali-metal perborates, alkali-metal chlorites, urea peroxides, combinations thereof, etc.

45 In the preferred form of this invention, the pre-neutralizing agent will be of the acidic oxidation type. This will function as an oxidizing agent and also serve to reduce the pH of the hair waving composition to arrest the action of the latter. Solutions of any persulfate or bromate oxidizing agent having a pH below 7 are particularly suitable for this purpose. By way of example the following may be mentioned: ammonium persulfate, potassium persulfate, sodium bromate, potassium bromate.

50 The quantity of pre-neutralizing agent that may be con-

tained in the pre-neutralizing composition can vary over a wide range, depending on whether the hair to be waved is bleached or tinted with oxidation dye compositions, and on the strength of the waving lotion chosen for use. In most cases, however, it will take the form of an aqueous solution of an oxidizing agent containing from 0.5 to 5.0% active oxygen having a pH between 3.5 and 7.0. In addition, it may also contain other ingredients such as wetting agents, thickeners, opacifiers, perfume oils, preservatives, stabilizers, film formers, hair conditioners, etc.

Hair waving compositions containing a reducing agent as the principal active ingredient are most suitable for use with the present invention. Of particular utility are solutions of thioglycollic acid or its derivatives (e.g. amides, esters, etc.) having a pH in the range of 7.0 to 9.4 and a concentration of reducing agent expressed in terms of thioglycollic acid ranging from 0.5 to 9.0%. These solutions may contain as the alkali any of the following, either alone or in combination with each other, e.g., ammonia, alkali-metal cations, alkaline earth cations, primary, secondary or tertiary amines (e.g. ethylamine, diethylamine, triethylamine), primary, secondary or tertiary alkanolamines (e.g., monoethanolamine, diisopropanolamine, triethanolamine), or cyclic amines, such as morpholine.

It is further to be understood that the present invention is applicable to hair waving compositions which comprise simple aqueous solutions of the active hair-waving agent, as well as more elegant compositions which may contain opacifiers, emulsifiers, perfumes, thickening agents, film formers, hair conditioners mentioned above.

In the practice of the present invention, hair previously bleached and retouched or subjected to multiple tintings with oxidation dye compositions so as to render the hair non-uniformly porous is pretreated with the pre-neutralizing agent, preferably in the form of an aqueous solution. The time of treatment may vary, depending upon the agent used. In general, the treatment will last from 1 to 20 minutes and preferably for about 10 minutes.

The hair so treated may then be given a usual cold hair waving treatment using any of the above-mentioned hair waving agents. This treatment may also vary between 1 and 20 minutes. However, it will usually last 10 minutes. The hair is then rinsed and neutralized according to prior art practices.

Although applicants do not want to be bound by any theory of action, the manner in which the present invention is thought to operate is set forth below. Because of the non-uniformity in the porosity of hair which has been subjected to multiple bleaching operations or tintings with oxidation dye compositions, the pre-neutralizing agent is absorbed into the hair structure in different amounts in different sections of the hair.

In most cases the greatest absorption takes place at the end section of the hair and the least absorption takes place at the root section. When the cold waving solution is applied, it is subjected to the greatest degree of neutralization in those hair sections which have absorbed the most pre-neutralizing agent. At any one site, however, there is more waving lotion than pre-neutralizing agent so that waving of the hair can be effected. The result is a more level overall wave without damage to the more porous sections of the hair, i.e. the end sections.

The above has been verified experimentally by the following experiments:

Hair bleached to resemble root, shaft and ends, as described above, was treated with 3% aqueous ammonium persulfate for 10 minutes. It was then waved out in the usual manner mentioned supra for about 10 minutes using waving lotion "T" described in Table I above and neutralized with a 12% aqueous solution of sodium bromate. The wet waving efficiencies and strengths were determined. The results are shown in Tables III and IV.

TABLE III.—COMPARISON OF WET WAVING EFFICIENCY USING WAVING LOTION "T" AS DESCRIBED ABOVE

Hair Used	Pretreated Hair	Non-Pretreated Hair
Root.....	55	50
Shaft.....	55	70
Ends.....	55	65

The results in Table III above show that uniform waving of root, shaft and ends are obtained by following the pretreating procedure of the present invention, whereas no such uniformity is obtained with the non-pretreated hair.

TABLE IV.—RELATIVE COMPARISON OF HAIR STRENGTHS (TENSILE STRENGTH)

Hair used.....	Ends
Lotion "B":	
Pretreated Hair.....	16
Non-Pretreated Hair.....	9
Lotion "B" diluted half strength:	
Non-pretreated hair.....	13

Table IV illustrates the increase in hair strength that attends the practice of the present invention, the higher number indicating the greater strength. In the first two columns the relative strength of hair waved with lotion "B," described in Table I, is set forth. The hair in Column 1 was first pretreated with 3% aqueous ammonium persulfate for 10 minutes in accordance with this invention. The hair in Column 2 was given no such pretreatment. The increase in hair strength is obvious. Column 3 shows that hair which has not been pretreated in accordance with the present invention is not as strong as hair treated in accordance with the present invention, even when the waving lotion applied to the former is half the strength of that applied to the latter.

Practical bleached and oxidation dye tinted head tests confirmed the above data. A commercial permanent wave for bleached hair was compared, by half-head tests, with the method of pretreating the hair with ammonium persulfate followed by waving with a lotion for tinted hair and neutralizing in the accepted manner. The following results were obtained:

Pretreatment process:	Commercial
(1) Uniform wave	Tight wave at the ends.
(2) Soft feel when dry ..	Harsh feel when dry.
(3) Firm when wet	Mushy when wet.
(4) No breakage on comb out	Breakage on comb out.

Similar results were obtained with the following basic systems on bleached hair:

(1) Pretreatment solution, 1.5% aqueous solution of ammonium persulfate. Waving lotion, 6.4% aqueous solution of thioglycollic acid + 2% NH₃. Lotion adjusted to a pH of 7.8 with acetic acid.

(2) Pretreatment solution, 3.0% aqueous solution of ammonium persulfate. Waving lotion, 8.7% aqueous solution of thioglycollic acid + 2.5% NH₃. Lotion adjusted to pH 7.8 with acetic acid.

Similar comparative results were obtained with half head tests conducted on tinted heads with the following basic systems:

(1) Pretreatment solution, 1.5% aqueous solution of ammonium persulfate. Waving lotion, 5.0% aqueous solution of thioglycollic acid + 1.2% NH₃. pH adjusted to 9.2 with sodium hydroxide.

(2) Pretreatment solution, 1.5% aqueous solution of ammonium persulfate. Waving lotion, 5.0% aqueous solution of thioglycollic acid + 3.3% monoethanolamine + 0.5% NH₃. pH 9.1-9.2.

In Table V below are given three additional examples of basic waving lotion formula which may be used in connection with the pre-neutralizing treatment on bleached hair. Each of the lotions is an aqueous solution containing the amount and ingredients indicated.

7
TABLE V

Percent NH ₃	Percent Thioglycollic Acid	Percent Monoethanolamine	Percent Triethanolamine	pH
1. 1.4.....	6.0	4.0	-----	9.2
2. 0.....	6.0	-----	10.0	8.2
3. 0.....	3.0	-----	5.0	7.2

In Table VI below are given two additional examples of basic waving lotion formula which may be used in connection with the preneutralizing treatment on tinted hair. Each waving lotion is likewise an aqueous solution containing the amount and ingredients indicated.

TABLE VI

Percent NH ₃	Percent Thioglycollic Acid	Percent Monoethanolamine	Percent Triethanolamine	pH
2.1.....	5.6	-----	10.0	7.9
0.5.....	6.0	-----	-----	9.2

Although the invention has been described with reference to specific forms thereof, it will be understood that many changes and modifications may be made without departing from the spirit of this invention.

What is claimed is:

1. A process for uniformly waving non-uniformly porous hair resulting from previous bleaching treatments which comprises pretreating said bleached hair with a dilute aqueous composition of an acidic oxidizing agent selected from the group consisting of ammonium persulfate, potassium persulfate, sodium bromate and potassium bromate and mixtures thereof, and subsequently subjecting said pretreated hair to the cold waving action of an aqueous alkaline composition of thioglycollic acid, whereby said hair is given a uniform wave.

2. A process according to claim 1 including the step of applying an oxidative neutralizing agent to said hair subsequent to the application of the hair waving composition whereby the action of the latter is arrested.

3. A process for uniformly waving non-uniformly porous hair resulting from previous treatment with a tinting oxidation dye composition containing an oxidizing agent which comprises pretreating said previously tinted hair with a dilute aqueous composition of an acidic oxidiz-

ing agent selected from the group consisting of ammonium persulfate, potassium persulfate, sodium bromate, potassium bromate and mixtures thereof and subsequently subjecting said pretreated hair to the cold waving action of an aqueous alkaline solution containing thioglycollic acid, whereby said hair is given a uniform wave.

4. A process according to claim 3 including the step of applying an oxidative neutralizing agent to said hair subsequent to the application of said hair waving composition whereby the action of the latter is arrested.

5. A process for uniform waving non-uniformly porous hair resulting from previous bleaching treatments which comprises pre-treating said bleached hair with a dilute aqueous composition of an oxidizing agent selected from the group consisting of hydrogen peroxide, alkali-metal bromates, alkali-metal perborates, alkali-metal chlorites, urea peroxides and mixtures thereof, and subsequently subjecting said pre-treated hair to the cold waving action of an aqueous alkaline composition of thioglycollic acid, whereby said hair is given a uniform wave.

6. A process for uniformly waving non-uniformly porous hair resulting from previous treatment with a tinting oxidation dye composition containing an oxidizing agent which comprises pre-treating said previously tinted hair with a dilute aqueous composition of an oxidizing agent selected from the group consisting of hydrogen peroxide, alkali-metal bromates, alkali-metal perborates, alkali-metal chlorites, urea peroxides and mixtures thereof, and subsequently subjecting said pre-treated hair to the cold waving action of an aqueous alkaline solution containing thioglycollic acid, whereby said hair is given a uniform wave.
